RECIPROCATING ROTARY DISTRIBUTING
PUMP

Alexander Dreisin, Chicago, and Raymond E. Peterson, Riverside, Ill., assignors to International Harvester Company, a corporation of New Jersey

Application May 31, 1945, Serial No. 596,860

8 Claims. (Cl. 103—2)

1

This invention concerns pumps utilizable in fuel injection systems of internal combustion engines, and more specifically relates to pumps of the type employing a plunger reciprocated within a rotating cylinder in such timed relation as to effect pressure strokes during registration of a cylinder outlet port with respectively different fuel delivery passages.

The general object of this invention is the provision of a unique and practicable plunger-controlled-port pump wherein the cylinder rotates synchronously with reciprocation of the plunger to establish communication with fuel delivery channels in succession at intervals respectively co-existent with the pressure or fuel delivery strokes of the plunger.

A more comprehensive understanding of this general object, as well as ancillary objects and the means of their attainment, can be had from the ensuing description with reference to the 20 annexed drawings, wherein:

Fig. 1 is a vertical sectional view taken centrally through a fuel injection pump constructed according to the principles of this invention.

Fig. 2 is a vertical sectional view taken on the 25 line 2—2 of Fig. 1.

Fig. 3 is a plan view of the pump.

Fig. 4 is a fragmentary sectional view taken upon the vertical plane indicated by the lines 4—4 in Figs. 3 and 5.

Fig. 5 is a horizontal sectional view taken on the line 5—5 of Fig. 4.

Fig. 6 is a horizontal sectional view taken on the line 6—6 of Fig. 4.

The pump herein disclosed embodying the preferred form of the invention, is of the single plunger type and is for delivering fuel to the combustion chambers of a four-cylinder engine.

Referring to Fig. 1, the casing 11 of the pump comprises a lower portion 12 to which an upper or cap portion 13 is secured by four cap screws 14 spaced circumferentially of the casing, as illustrated in the plan view of Fig. 3. The cap portion 13 of the casing has a cylindrical bore 15 which serves as a bearing and sealing surface for a rotatable cylinder 16. Cylinder 16 contains a bore 17 in which a pump plunger 18 (normally constrained against rotation) is reciprocable during rotation of the cylinder. During reciprocation of the plunger, fuel is alternately

drawn into a fuel charging zone 19 in the upper end of the cylinder bore 17 through inlet and bypass port means 21 and expelled through an outlet port 22. The manner with which the fuel charging zone 19 is alternately charged with fuel and has the fuel expelled therefrom will be explained more fully hereinafter. Reciprocation of the plunger 18 is effected conventionally by the cooperation of a helical spring 23, a cam 24 on a pump drive shaft 25, and a cam follower structure 26 which includes a roller 27 which follows the periphery of the constantly rotating cam 24. This cam has four equally spaced lobes 28 of which the profile is illustrated in Fig. 2.

Power for driving the pump shaft 25 is received through a flanged coupling member 29, Fig. 1, which is keyed to said shaft at 31. Since there are four lobes on the cam 24, the cam follower 26 and the plunger 18 will be caused to make four complete reciprocal excursions for each revolution of the drive shaft. Pressure fluctuations within the casing chamber 32 during reciprocation of the plunger are modulated by the movement of air in a breather passage 33 formed integrally with a cover plate 34 secured to the side of the casing by any standard means. Air entering the pressure passage 33 is filtered through a filter device 35.

A power train for rotating the cylinder 16 comprises a worm gear 36 formed integrally with the 30 shaft 25, a companion worm gear 37 keyed to a vertical shaft 38, Fig. 2, a gear 39 formed integrally with the upper end of the shaft 38, and a gear 41, Figs. 1, 2, and 4 driven by the gear 39 and formed integrally with the lower end of said cylinder. This power train drives the cylinder 16 at the same speed as the drive shaft 25. Consequently there are four complete reciprocal movements of the plunger 18 for each complete rotation of the cylinder 16.

As the cylinder 16 rotates, the outlet port 22 therein is swept successively over fuel delivery or outlet passages 42, of which there are four, which communicate with the casing bore 15 at 45 equally spaced positions circumferentially of said bore. The upper ends of upwardly extending portions of the passages 42 are enlarged and threaded for the reception and connection of conduit coupling members 43. The arrangement of these coupling members 43 with respect to the cap

screws 14 is illustrated in Fig. 3. Conduits (not shown) lead from the coupling members 43 to respective combustion chambers of the engine. Check valves generally designated 44 are contained in the coupling devices 43 to permit outward flow of fuel through the passages 42 but to prevent fuel flow in the opposite direction from the aforesaid combustion-chamber-connecting conduits into said passages.

Fuel inlet means within the casing 11 comprises a circular cavity 45, Figs. 1 and 6, formed eccentrically with respect to the bore 15 for the cylinder 16. Fuel is supplied to the cavity 45 through diametrically opposite passages 46 under pressure from a primary pump (not shown). Threaded sections 47 at the outer ends of the passages 46 facilitate the connection of conduit means leading from the primary pump. When the plunger 18 approaches the lower limit of its stroke, in which position the plunger is illustrated in the drawings, the fuel under pressure in the cavity 45 rushes into the fuel charge receiving zone 19, Fig. 1, through the fuel inlet and by-pass ports 21 to fill this zone with a charge of fuel. During the ensuing upward or advancement stroke of the plunger, fuel is expelled through the by-pass ports 21 until the plunger advances far enough to cover these ports. Thereafter, upward advancement of the plunger compresses the fuel within the zone 19 and expels compressed fuel through the outlet port 22 which is so positioned upon the cylinder 16 as to be then registered with one of the outlet passages 42. Consequently, the fuel expelled through the outlet port 22 will flow outwardly of the pump through one of the passages 42 and its associated check valve 44 to cause delivery of fuel to the associated combustion chamber. In Figs. 1, 4, and 6 there is illustrated on the side wall of the plunger a side wall cavity 48 constituting a by-pass means successively cooperable with the four inlet and by-pass passage ports 21 for interrupting the discharge of fuel from the fuel charge zone 19 through the outlet port 22. This side wall cavity 48 communicates with the fuel charge receiving zone 19 through an L-shaped passage 49 which opens outwardly through the upper end of the plunger. After the plunger 18 progresses a predetermined distance in its advancement stroke, the leading or metering edge 51 of the cavity 48 registers with and commences to establish by-pass communication with one of the ports 21, so that thereafter the fuel will be expelled from the zone 19 through said port 21 instead of through the outlet port 22 which communicates with the combustion chamber.

The cavity 48 herein illustrated in Figs. 1 and 4 is formed upon the plunger by effecting a milling cut in such a manner as to dispose the metering edge 51 diagonally of the plunger axis. Thus by rotatively adjusting the plunger, the time at which the metering edge 51 registers with one of the ports 21 for terminating fuel injection can be varied. Rotational adjustment of the plunger is obtained conventionally by means of a gear 52 carried rotatively in the casing coaxially of the plunger. The plunger is free to move endwise relatively to the gear 52, and the latter has a downwardly projecting sleeve-like portion 53 containing an axially extending slot 54 in which a projection 55 on the plunger slides. A rack R, Fig. 3, having gear teeth meshed with the teeth of the gear 52 is employed for controlling the rotational position of this gear and consequently through the agency of the slot 54 and the plunger

projection 55 to likewise control the rotational position of the plunger and of the metering edge 51 of the side wall cavity 48.

The plunger 18 is illustrated at the mid-position of its rotational fuel control position. In this position the end 56, Fig. 6, of the metering edge 51 is in radial registry with the radial line associated with the notation "mid-position." When the plunger is rotated counter-clockwise as viewed in Fig. 6, as indicated by the arrow associated with the notation "fuel increase," such a distance as to bring the end 56 of said metering edge into registration with the radial line having the notation "maximum fuel" associated therewith, the apparatus will be adjusted for the delivery of maximum fuel. By rotating the plunger counter-clockwise, a section of the metering edge spaced more distantly from the upper end of the plunger is positioned for first arriving in registry with one of the by-pass ports 21 for effecting by-pass during the fuel delivery strokes of the plunger, to thereby increase the time period of injection and correspondingly increase the quantity of injected fuel. By rotating the plunger clockwise as viewed in Fig. 6, the opposite effect is obtained of placing a section of the metering edge 51 less distantly spaced from the upper end of the plunger for first arriving in registry with one of the by-pass ports 21 during injection strokes of the plunger. The minimum fuel adjustment within the operating range for the engine is attained when the plunger is rotatively adjusted to bring the end 56 of said metering edge into radial registry with the radial line having the notation "no fuel."

In further explaining the operation of the pump, the sequential functioning of the parts will be related during the cycle of one-quarter of the drive shaft 25, which cycle is just ready to commence as the parts are illustrated in the drawings. Such cycle of operation occurs while the cam lobe 28 shown to the right of the cam follower roller 27, Fig. 2, passes beneath such roller for ultimate arrival at the position in which the lobe 28 to the left of said roller is shown. As the parts are shown in the drawings, the plunger 18 is at its lower limit of retractive movement whereby the by-pass ports 21 are uncovered and fuel is rushed into the zone 19 through said ports. As the pump drive shaft 25 and the cam 24 rotate counter-clockwise as viewed in Fig. 2, the cam lobe to the right of the roller 27 will first commence to raise this roller and the plunger for advancing the latter upwardly. When the roller 27 has ascended a short distance up the leading profile of this cam lobe, the advancing stroke of the plunger 18 will have progressed far enough to cause the plunger to cover the by-pass ports 21 and trap the fuel charge within the zone 19. Meanwhile, the power train including the gear pairs 36-37 and 39-41 will have rotated the cylinder 16 somewhat clockwise of the position shown in Figs. 5 and 6 to carry the outer enlarged end of the outlet port 22, Fig. 5, into communication with outlet passage 42, which it is shown to be approaching, and to carry the by-pass port 21 shown at position b toward the position c. As the plunger continues to rise and as said by-pass port moves toward the position c, and at which time the outlet port 22, Fig. 5, has already reached registration with the next adjacent outlet passage 42, the fuel will be forced outwardly through said port 22 into said channel 42. This expelling action through the port 22 and said channel 42 prevails until the plunger

rises sufficiently far to carry the metering edge 51 into partial registration with the by-pass port 21 which is then between the positions *b* and *c*, whereupon the expelling of fuel through the port 22 ceases and by-pass occurs downwardly through the L-shaped plunger passage 49, the plunger cavity 48, and the said port 21 into the fuel inlet cavity 45. When the cam lobe under discussion is moved an amount corresponding to forty-five degrees rotation of the drive shaft 25 to place the apex of this lobe beneath the follower roller 27, whereby the advancement stroke of the plunger is complete, the port 21 under discussion will arrive in registry with the line *c* in Fig. 6, whereas the outlet port 22 in Fig. 5 will have just passed over the outlet passage 42 under discussion shown adjacently thereto in Fig. 5. During the succeeding forty-five degrees of drive shaft rotation, the spring 23 by keeping the cam follower roller 27 in contact with the descending profile of said cam lobe, will cause the plunger to effect its retraction stroke for returning it to the position illustrated in the drawings. Attendant to this additional forty-five degree rotation of the drive shaft pursuant to which the cam lobe under discussion is moved forward to the position of the cam lobe 28 shown just to the left of the roller 27 in Fig. 2, the power train driving the rotatable cylinder 16 imparts an additional forty-five degree rotation to this cylinder to place the outlet port 22, Fig. 5, in the same relation to the outlet passage 42 second ahead thereof as this port occupies with respect to the port shown adjacently thereto in Fig. 5, and such additional forty-five degree rotation of the cylinder carries the by-pass port 21, under discussion, into the position occupied by the port nearest to the position *c* in the clockwise direction therefrom. A new charge will have entered the fuel charging zone 19 through the ports 21, and a new cycle is ready to commence. The only difference between the operation of the device in this succeeding cycle is that the outlet port 22 will register with the outlet passage 42 in the second position therefrom, as illustrated in Fig. 5, in the clockwise direction during the injection stroke instead of with the outlet passage 42 in the position nearest to said port in the clockwise direction. Of course, a succeeding cam lobe cooperates with the cam follower roller 27 in effecting movement of the plunger in this succeeding cycle. Since the plunger is caused to make four complete reciprocal movements for each revolution of the cylinder 16, the outlet port 22 of the cylinder successively registers with the outlet passages 42, Fig. 5, during the successive injection strokes of the plunger, to properly sequentially supply fuel to the combustion chambers of the engine with which the pump is cooperable.

Attention is directed to an arcuate sealing means in the form of a curved cylinder surface 57, Fig. 6, formed upon a side wall of the casing cavity 45 for cooperation with the outer periphery of the cylinder 16 in sealing the outer ends of the by-pass ports 21 as they approach the position for cooperation with the by-pass cavity 48 of the plunger. The purpose of this sealing surface 57 is to prevent premature cooperation of the ports 21 with said plunger cavity. By way of illustration, if the plunger were rotated to the maximum fuel position illustrated in Fig. 6, the fuel metering edge 51 would be in position for registering with the port 21 approaching the position *a* as well as the port 21 approaching the position *c*, and since the slope of said diagonal edge

is such that its end 56 is nearer the upper end of the plunger than the opposite end of such metering edge, the port approaching the position *a* is uncovered prior to the port approaching the position *c*. However, the apparatus is designed for the metering edge 51 to cooperate with the by-pass port 21 approaching the position *c* in determining the time of by-pass and the quantity of the fuel charge. Mis-operation of the device is prevented by providing the sealing surface 57, which seals the outer end of the port approaching the position *a*, so that registration of the plunger cavity with this port is unimportant. During the injection stroke, the ports 21 other than those ports 21 respectively approaching the positions *a* and *c* remain covered at their inner ends by the cylindrical periphery of the plunger, and it is the purpose of the additional sealing means 57, which slidably engages the outer periphery of the cylinder 16, to supplement the said cylindrical periphery of the plunger in covering the by-pass ports while they are out of the position for intended registration with the cavity of the advancing plunger. Sealing surface 57 provides an expedient making it possible to increase the number of by-pass ports 21 spaced circumferentially about the cylinder and correspondingly to increase the number of possible combustion chambers which the pump is capable of supplying with fuel.

Having thus described a preferred embodiment of the invention with the view of clearly illustrating the same, we claim:

1. In a fuel pump; a casing containing a cylinder-receiving bore, fuel inlet means at a section of said bore and a plurality of fuel outlet passages communicating with said bore in circumferentially spaced relation thereabout and spaced axially of the bore from the fuel inlet means; a cylinder in said bore, said cylinder having a set of inlet ports disposed for communication between said fuel inlet means and a fuel charging zone within the cylinder, said inlet ports being spaced circumferentially of the cylinder, the cylinder also having an outlet port for the fuel charging zone and spaced axially of such cylinder from the inlet ports in position for successive registration with the outlet passages during rotation of the cylinder; a plunger reciprocable in the cylinder, while the latter rotates relatively thereto, to charge said fuel charging zone through the inlet ports during retractive reciprocal strokes and to discharge the fuel charge from said zone through the outlet port during the intervening advancement strokes; means for reciprocating the plunger in timed relation with rotation of the cylinder to effect such advancement strokes of the plunger during respective registration of the outlet port with the outlet passages; and fuel by-pass means on said plunger to establish communication between the charging zone of the cylinder and successive of the inlet ports during successive advancement strokes of the plunger following predetermined movement thereof in such advancement strokes.

2. In a fuel pump; a casing containing a cylinder-receiving bore, fuel inlet means at a section of said bore and a plurality of fuel outlet passages communicating with said bore in circumferentially spaced relation thereabout and spaced axially of the bore from the fuel inlet means; a cylinder in said bore, said cylinder having inlet port means disposed for communication between said fuel inlet means and a fuel charging zone within the cylinder, the cylinder also hav-

ing an outlet port for the fuel charging zone and spaced axially of such cylinder from the inlet port means and in position for successive registration with the outlet passages during rotation of the cylinder; a plunger reciprocable in the cylinder, while the latter rotates relatively thereto, to charge said fuel charging zone through the inlet port means during retractive reciprocal strokes and to discharge the fuel charge from said zone through the outlet port during the intervening advancement strokes; means for reciprocating the plunger in timed relation with rotation of the cylinder to effect such advancement strokes of the plunger during respective registration of the outlet port with the outlet passages; and fuel by-pass means on said plunger to establish communication between the charging zone of the cylinder and the inlet port means during each advancement stroke of the plunger following predetermined movement thereof in such advancement strokes.

3. In a fuel pump; a rotatable cylinder having a plurality of circumferentially-spaced by-pass ports, an outlet port and a fuel charging zone with which all of said ports are communicative; a plunger reciprocable in the cylinder, while the latter rotates relatively thereto, to charge said zone with fuel during retractive reciprocal strokes and to eject fuel of such charge from said zone through the outlet port during the intervening advancement strokes; said plunger being operable to cover all of said by-pass ports to prevent escape of the fuel charge therethrough during an initial portion of the advancement strokes, said plunger also having a side-wall cavity communicative with the fuel charging zone and occupying such a position on the plunger as to register with different of said by-pass ports of the rotating cylinder during successive advancement strokes, to establish a by-pass condition for the fuel charging zone during an ensuing portion of such strokes.

4. The combination set forth in claim 3, wherein the plunger is rotatively adjustable and said side-wall cavity thereof has a leading metering edge which first arrives in registry with the by-pass ports, and wherein the cavity edge is arranged diagonally of the plunger axis to vary the time of incurring by-pass in accordance with rotative adjustment of the plunger.

5. In a fuel pump; a rotatable cylinder having a plurality of circumferentially-spaced radially-extending by-pass ports communicative with a fuel charge zone of the cylinder at their inner ends and also having an outlet port communicative with said zone; a plunger reciprocable in the cylinder, while the latter rotates relatively thereto, to charge said zone with fuel pursuant to retractive reciprocal strokes and to expel fuel of such charge from said zone through the outlet port during the intervening advancement strokes; said plunger being operable to cover at least one of said by-pass ports to prevent escape of the fuel charge therethrough during an initial portion of the advancement strokes, said plunger also having a side-wall cavity communicative with the fuel charging zone and occupying such a position on the plunger as to register with a different of said by-pass ports of the rotating cylinder during successive advancement strokes, to establish a by-pass condition for the fuel charging zone during an ensuing portion of such strokes, and sealing means slidingly engaging the outer periphery of said cylinder to supplement said plunger in covering the by-pass ports while

they are out of position for intended registration with the cavity of the advancing plunger.

6. In a fuel pump; a rotatable cylinder having a plurality of circumferentially-spaced radially-extending by-pass ports communicative with a fuel charge zone of the cylinder at their inner ends and also having an outlet port communicative with said zone; a plunger reciprocable in the cylinder, while the latter rotates relatively thereto, to charge said zone with fuel pursuant to retractive reciprocal strokes and to expel fuel of such charge from said zone through the outlet port during the intervening advancement strokes; means for covering said by-pass ports to prevent escape of the fuel charge therethrough during the advancement strokes, and cavity means in a side wall of the plunger, said cavity means being communicative with the fuel charging zone and occupying such a position on the plunger side wall as to register with a different one of said by-pass ports of the rotating cylinder during successive advancement strokes of the plunger.

7. In a fuel pump; a rotatable cylinder having a plurality of circumferentially-spaced radially-extending by-pass ports communicative with a fuel charge zone of the cylinder at their inner ends and also having an outlet port communicative with said zone; a rotatively adjustable plunger reciprocable in the cylinder, while the latter rotates relatively thereto, to charge said zone with fuel pursuant to retractive reciprocal strokes and to expel fuel of such charge from said zone through the outlet port during the intervening advancement strokes; the side wall of said plunger being operable to cover and seal the by-pass ports during the advancement strokes but having a side wall cavity which communicates with the fuel charge zone and which is registerable with the by-pass ports after predetermined progress in the advancement strokes to cooperate therewith in thereupon interrupting ejection of the fuel charge, said cavity having a fuel control range wherein it is adjustable circumferentially of the plunger axis pursuant to rotational adjustment of the plunger and the cylinder being rotatable in timed relation with the reciprocation of the plunger to successively present the by-pass ports in said range for individual cooperation with the plunger cavity during the advancement strokes, said cavity having a leading metering edge which first uncovers each by-pass port when it is disposed for cooperation with said cavity and such metering edge being arranged diagonally of the plunger axis to cause variation in the advancement stroke progress preceding by-pass in accordance with rotative adjustment of the plunger, and sealing means disposed at the outer periphery of said cylinder in radial registration with an end portion of said fuel control range to supplement the sealing function of the plunger side wall by covering and sealing the outer ends of by-pass ports adjacent to those presented for individual cooperation with the plunger cavity, when the circumferential spacing of said ports is sufficiently close for the adjacent ones thereof also to be uncovered by said cavity.

8. In a fuel pump; a rotatable cylinder having a fuel charge zone, a plurality of circumferentially-spaced sidewall by-pass ports adjacently to one end of such zone and an outlet port communicating with said zone adjacently to the other end thereof; a plunger reciprocable in said cylinder to charge said zone with fuel during retraction strokes and to expel fuel of such charge through the outlet port during advancement strokes, said

plunger covering said circumferentially-spaced ports while advanced from the retraction terminus of its strokes and having a side-wall cavity communicating with said zone, said cavity being disposed for registration with any of said by-pass ports when the plunger has progressed predeterminedly in its advancement stroke; and means for rotating the cylinder relatively to the plunger in timed relation with reciprocating said plunger to successively advance the by-pass ports into position for registration with the plunger cavity during successive advancement strokes of the plunger.
